(57) **CLAIM**

We claim the ornamental design for a sliding bathroom sink drawer, as shown and described herein.

DESCRIPTION

FIG. 1 is a perspective view of our sliding bathroom sink drawer shown in an in-use location;

FIG. 2 is a perspective view of the drawer shown in FIG. 1;

FIG. 3 is a top view thereof;

FIG. 4 is a bottom view thereof;

FIG. 5 is a front view thereof;

FIG. 6 is a rear view thereof;

FIG. 7 is a right side elevational view thereof with the left side elevational view being a mirror image thereof; and,

FIG. 8 is a perspective view of an alternative embodiment of our drawer, shown broken apart to indicate the adjustability of the drawer width.

The broken lines showing in the drawings are for illustrative purposes only and form no part of the claimed design.
